Specification of Letters Patent. Patented Feb. 22, 1916.

Application filed August 19, 1914. Serial No. 857,576.

To all whom it may concern:

Be it known that we, FERDINAND W. NITARDY and HERBERT C. SCHAEFER, citizens of the United States, both residing at Denver, in the county of Denver and State of Colorado, have invented certain new and useful Improvements in Bottles, of which the following is a specification.

This invention relates to improvements 10 in bottles and other vessels of similar character, and more particularly in containers of the construction shown and described in the application for patent of Ferdinand W. Nitardy, Serial No. 828,041, filed March 28, 15 1914.

The containers above referred to are provided with a channel or passage which is capable of diverting the drippings from the mouth of the vessel away from a determinate side of the same, for the purpose of preventing the liquid from smearing and obliterating the writing or printing on the face of a label attached to the vessel at its said side.

25 The channel or passage is to this end disposed to receive the liquid dripping from the outer edge of the mouth of the bottle when the latter has been restored to an upright position after usage, and it is formed 30 to conduct the liquid to a point or points remote from the labeled side of the vessel.

While the means provided for this purpose as shown in the above-mentioned application for patent, adequately performed 35 their functions, it was found that in some cases the liquid drying on the sides of the bottle other than that to which the label was applied, produced an objectionable sticky coating, that in other instances the liquid 40 flowing down the sides of the bottle soiled the surface of the table or other article on which the bottle was supported, and that on bottles which carry more than one label, the label on one of its sides would be wetted 45 and defaced, while that on the other side remained clean and free from moisture.

It is the object of the present invention to eliminate the above-mentioned objectionable features of the construction originally 50 disclosed in the above referred to application for patent, by providing the bottle in addition to the channel which receives the liquid dripping from its opening, with one or more additional channels which extend

downwardly along its sides in connection 55 with the first-mentioned channel to conduct the liquid along determinate courses to the bottom portion of the vessel.

Another object of the invention resides in providing means for retarding or retaining 60 drippings passing along the above-mentioned courses, to prevent their flowing onto the surface on which the bottle is placed.

The improvements above mentioned have been illustrated in the accompanying drawings, in the various views of which like parts are similarly designated, and in which,

Figure 1, represents a rear elevation of my improved bottle, Fig. 2, a side elevation of the same, Fig. 3, a top view of the bottle, Fig. 4, a fragmentary section taken along the line 4—4, Fig. 3, and drawn to an exaggerated scale, Fig. 5, a fragmentary elevation of the bottom portion of a bottle showing a modified construction of the 75 means for retaining liquid dripping from the opening of the bottle, and Fig. 6, a section taken along the line 6—6, Fig. 5, drawn to an exaggerated scale.

The bottle shown in the drawings has a passage or channel 2 to receive the liquid dripping from the rim 3 of its neck 4 at its side at which the label 5 is attached. The channel is preferably produced by a ridge 6 formed on the shoulder 7 of the bottle between its neck and its body-portion 8, and extending from a central point at the label-side of the vessel in opposite directions to points in the edge of the shoulder at the opposite side of the same. The outer ends of the channel 90 thus formed, connect with grooves 9 which extend downwardly to the bottom of the vessel, and which may be provided with a series of transverse ripples 10 for the purpose of retarding the downward flow of liquid 95 passing through the grooves. When a bottle to which the improvements are applied is square or polygonal in cross section, the grooves are preferably formed along the lines at which the sides of the vessel 100 adjoin, thereby to prevent the liquid from soiling any surface of the bottle which may be touched in handling. The transverse ripples in the grooves are provided to retard the downward flow of the liquid for the purpose of causing it to be retained by adherence, or of permitting it to evaporate before it has reached the bottom of the vessel. By

spacing the ripples in accordance with standard measurements of the contents of the bottle, such as fluid ounces, and designating them approximately by figures or other characters, the ripples may serve in addition to their other function, to indicate the amount of liquid contained in the vessel, or to measure a dose of medicine to be taken therefrom.

10 In the construction shown in Figs. 5 and 6, the channels 9 at the edges of the body portion of the bottle, terminate at their lower ends in a transverse trough 12 formed by a groove in the side of the bottle, which receives and retains the liquid flowing through the said channels, and thus prevents it from soiling the table or other surface on which the bottle is placed.

We desire it understood that the form and arrangement of the improvements shown and described in connection with a medicine bottle of rectangular section, may naturally be varied in accordance with the shape and construction of other, different vessels to which they are applied, within the spirit of our invention as defined in the following claims:

1. A container having an opening and a channel or passage positioned to receive liquid dripping from an edge of said opening, a groove in the body portion of the container for conducting said liquid to the bottom portion of the vessel, and transverse ripples in said groove for obstructing the downward flow of liquid.

2. A container having an opening, conductive means positioned to receive liquid dripping from an edge of said opening, and adapted to conduit said drippings along a determinate course to the bottom portion of the container, and means for obstructing the downward flow of liquid along said course.

3. A container of angular section having an opening, a shoulder between said opening and the body portion of the container, a channel or passage formed on said shoulder to receive liquid dripping from an edge of said opening, grooves formed in the body portion of the container along the edges of the same, defined by two of its angles, in connection with opposite ends of said channel or passage, for conducting liquid to the bottom portion of the container, and means in connection with said grooves for obstructing liquid flowing through the same.

In testimony whereof we have affixed our signatures in presence of two witnesses.

FERDINAND W. NITARDY.
HERBERT C. SCHAEFER.
